PIN ELEVATING MECHANISM FOR BOWLING
PIN SPOTTING MACHINES

Henry C. Congelli, Stamford, Conn., and Robert L. Holloway, Snyder, N.Y., assignors to American Machine & Foundry Company, a corporation of New Jersey

Filed Dec. 26, 1957, Ser. No. 705,335

18 Claims. (Cl. 273—43)

The present invention relates to automatic bowling pin spotting machines and more particularly to improved mechanism for removing bowling pins from the pit of a bowling alley and elevating them to a point of discharge above the pit where pins are discharged into a pin aligning device for aligning and transfer to a pin distributing mechanism for ultimate delivery to a bowling pin spotter.

In bowling pin spotting machines, and in particular automatic bowling pin spotting machines, it is desirable that bowling pins falling into the pit of a bowling alley be removed as quickly as possible therefrom and delivered to a pin spotter which will spot them in playing configuration on a bowling alley in order that the play of a game can continue with as little interruption as possible. In most devices provided heretofore, bowling pins removed into the elevating member have been firmly held therein by separately actuated grippers, rods or clamps against removal during their transfer from the pit of the alley to a discharge station where the grippers are released and the pins are allowed to gravitate into an aligning and transfer device. In others of these devices, pins carried in the elevating member are slid against and engaged by stationary guide members to prevent removal during their transfer from the pit to the discharge station.

The present invention is characterized by the provision of an elevating device, which, by its novel construction, retains pins delivered thereto during their transfer from the pit of the alley to the elevated discharge station without the aid of grippers, rods or clamps. At the discharge station, when the pin spotting mechanism of the associated machine so requires, pins are simply urged out of the elevating mechanism into the aligning and transfer device.

Further, bowling alley proprietors often desire to use pins according to the demands of play at a particular time. In "open" play fairly old or used pins are satisfactory. In "league" play new or fairly new pins are required. Then from time to time changes of pins are necessary. Mechanism is provided in the present invention for automatically removing pins from the elevating mechanism before delivery to the aligning and transfer device. This permits safe and rapid pin changing in a bowling pin spotting machine employing an elevating device embodying the present invention since an attendant can feed new pins into the machine while it is operating and as the old ones are automatically being removed therefrom.

It is therefore an object of the present invention to provide an elevating device which freely retains pins therein during their transfer from the pit of a bowling alley to a discharge station.

It is a further object of the present invention to provide a rotary pin elevating device in the form of an annular member having a generally U-shaped circumferential channel into which bowling pins are delivered from the pit of a bowling alley and in which pins are loosely retained against removal by means forming a part of the elevating device.

An additional object of the present invention is to provide novel means for storing pins until they are required by the pin spotting mechanism of an automatic pin spotting machine.

2

A further object of the present invention is to provide novel means for ensuring the positive delivery of pins from the pin elevating mechanism into the pin orienting and transfer device of an automatic pin spotting machine.

It is an added object of this invention to provide automatic means for effecting the removal of pins from the elevating member to facilitate pin changing while the elevating member is in operation.

With these and other objects not specifically mentioned in view, the invention consists in certain combinations and constructions which will be hereinafter fully described, and then set forth in the claims hereunto appended.

In the accompanying drawings which form a part of this specification and in which like characters of reference indicated the same or like parts:

FIG. 1 is front elevation showing a preferred embodiment of the invention.

FIG. 2 is a side elevation of the mechanism shown in FIG. 1.

FIG. 3 is a view taken along line 3—3 of FIG. 1.

Referring to the drawings, the pin elevating mechanism, designated generally M, chosen to illustrate a preferred embodiment of the invention is shown mounted between kickbacks K of a conventional bowling alley (not shown). Bowling pins 10 and balls (not shown) removed into pit P from the playing surface of the associated alley are deposited onto the upper lap of a pit-wide conveyor or travelling apron 12. Conveyor 12, which preferably is continuously in motion in pit P, describes a path of travel around rollers 14, only one of which is shown, mounted on shafts 16 (only one shown), suitably supported in kickbacks K at the front and rear of pit P. Rollers 14 are driven in any convenient manner in the direction of arrow A in FIGURE 2 to deliver pins 10 and balls (not shown) deposited on conveyor 12 to the rear of pit P. Platform 18, suitably secured between opposed faces of kickbacks K, supports and prevents the upper lap of conveyor 12 from sagging under the load or impact of pins 10 and balls deposited thereon.

Balls deposited on conveyor 12 are separated from pins 10 by any suitable means and conducted to a ball return track (not shown) for eventual return to the bowler. Pins 10, thus separated from the balls, are delivered on conveyor 12 to chute 20 at the rear of pit P and adjacent mechanism M on which they slide or gravitate into pin elevating device M. Plows 22 and 24 located on opposite sides of conveyor 12 operate to direct pins 10 onto chute 20. As shown in FIGURE 2, pins 10 can actually roll down chute 20 and move or be moved into pin elevating mechanism M without the use of mechanical adjuncts.

Plows 22 and 24 are suitably secured to the respective inner faces of kickbacks K and act to divert pins 10 away from kickbacks K for discharge by conveyor 12 down chute 20 into pin elevating mechanism M. Plows 22 and 24 have surfaces 26 which conform generally with the curve of the outer periphery of pin elevating mechanism M. Thus, any pin 10 not properly aligned or positioned in pin elevating mechanism M with its longitudinal axis substantially parallel with the circumference of mechanism M slides downwardly over surfaces 26 onto chute 20 or conveyor 12 or into the lowermost part of mechanism M for repositioning for proper elevation.

Conveyor 12, chute 20 and plows 22 and 24 may be similar in construction and operation to those shown in Holloway et al. Patent 2,767,983 for Bowling Pin Elevating mechanism and further disclosure thereof is omitted.

A preferred embodiment of pin elevating mechanism M comprises a rotary member 28 preferably of circular contour mounted to rotate in a substantially vertical plane. Rotary member 28 is formed of sheet metal parts,

or sections, although it may be made of light castings or otherwise produced to perform its desired functions. As shown in FIGURES 1 and 2, rotary member 28 is provided with a circular marginal rim or ring 30 which is attached to a pin receiving channel or wheel 36, although it may be formed as an integral part of channel or wheel 36, if desired.

Rotary member 28 is supported on spaced sheaves 38, 40, 42 and 44 rotatably mounted on horizontal shafts 46, 48, 50 and 52 respectively. Upper shafts 46 and 48 are fixed to upper cross-frames 54 secured transversely at the rear of rotary member 28 to kickbacks K. Lower shafts 50 and 52 are fixed to lower cross-frame 56 secured transversely at the rear of rotary member 28 to kickbacks K also (see FIGURE 1). Inclined supports 51 and 53 are secured at their upper ends to each side of cross-frame 54 adjacent pin discharge station S2 and at their lower ends to each side of cross frame 56 adjacent kickbacks K, adding structural rigidity to the entire framework. Upper sheaves 38 and 40 engage rim 30 which is preferably of circular cross-section adjacent each side of pin discharge station S2, while lower sheaves 42 and 44 engage rim 30 adjacent each side of pin pick-up station S1. Sheaves 38, 40, 42 and 44 thus support rotary member 28 for rotation in a substantially vertical plane.

Channel 36 is generally U-shaped in cross-section and preferably is formed with an outer marginal flange 58 which accommodates belt 60. Belt 60 runs on and is driven by sheave 62 fixed to shaft 63 of a suitable power source (not shown). Belt 60 is driven preferably continuously thus rotating member 28 through pit P in a substantially vertical plane in the direction of arrow B, as shown in FIGURE 1.

Fillers 64 are secured to rotary member 28 and equidistantly spaced in channel 36 to provide suitably shaped pin seats or pockets 66. Seven pockets 66 have been found to operate satisfactorily and for the purpose of illustration are shown employed in rotary member 28 illustrated in FIGURE 1. However, if desired, the number of pockets could be increased or decreased depending firstly, upon the diameter of pin elevating member M and secondly, the type of bowling pins handled; namely, ten pins, duck pins, candle pins or others.

Pin elevating member M is driven, preferably continuously through pit P. Pins 10 delivered to station S1 on conveyor 12, as described hereinabove, move or are moved over chute 20 and into channel 36 of member 28. Pins 10 seated in channel 36 of member 28 are carried upwardly either butt end first or handle end first in pockets 66 in the direction of arrow B in FIGURE 1 to pin discharge station S2. At station S2 pins 10 when released, as described hereinbelow, gravitate out of pockets 66 onto pin aligning and transfer mechanism T (partially shown) as the rotation member 28 travels each pocket 66 in succession therewith. Pin aligning and transfer mechanism T may be similar in construction and operation to that shown in Zuercher Patent 2,767,984 for Pin Distributing and Spotting Mechanism for bowling pin spotting machines and only so much as is required for a proper understanding of the present invention is included therein.

As indicated in FIGURE 1, pockets 66 are so constructed that they readily receive pins 10 lying lengthwise along and within channel 36 such that the axis of pins 10 lie in a plane generally transverse to the axis of rotation of member 28. Actually pins 10 cannot be supported for elevation in member 28 in any other position. Pins 10 discharged by conveyor 12 and entering endwise into pockets 66 may be turned or moved into proper position therein or fall back upon conveyor 12 until they are properly delivered into a pin pocket 66. Curtain or shield 29 is secured to lower cross frame 56 adjacent station S1 as shown in FIGURE 1 to deflect any pins 10 back onto conveyor 12 that might accidentally have been thrown rearwardly out of member 28 by the movement thereof when such pins 10 were not properly seated therein at Station S1.

Referring to FIGURE 1, pin discharge station S2 is shown substantially directly over station S1. If desired, station S2 may be located at some other position along the path of travel of channel 36 as long as space is provided for the release of pins 10 from pockets 66 into pin aligning and transfer device T.

To retain pins 10 in their respective pockets 66 during their elevation from pin pick up station S1 to pin discharge station S2, rotary member 28 is provided with a substantially circular rail 68, preferably of tubular construction, secured to and rotating with member 28. Rail 68 is fixed to fillers 64 at the inner periphery of channel 36 as shown in FIGURE 3. As a pin 10 in pocket 66 is elevated by member 28, the force of gravity may tend to dislodge it from its pocket 66 before it reaches discharge station S2. When a pin 10 during its elevation, attempts to gravitate out of pocket 66 it engages rail 68 which supports the pin 10 in pocket 66 against dislodging by gravity during its elevation toward station S2. Thus pins 10 will be freely retained in their respective pockets 66 for elevation, from station S1 to S2 and thence to pin aligning and transfer mechanism T.

At station S2, a selectively operable release mechanism is provided to urge pins 10 out of their respective pockets 66 when such pins are required during the cyclic operation of the associated bowling pin spotting machine. The release mechanism in the illustrated embodiment of the invention, comprises a push bar 70 pivotally mounted on stud 72 secured adjacent the upper edge of bracket 74. Push bar 70 is provided with a cam track 76. Cam follower 78 is fitted in track 76 and rotatably mounted on one end of arm 80, which is preferably of V-shaped configuration. Arm 80 is pivotally mounted adjacent its midpoint or substantially at the apex of the V on stud 81 secured to bracket 74. The other end of arm 80 is connected by spring 82 to the armature 84 of solenoid 86. One end of a second spring 88 is likewise connected to this end of arm 80 while the other end of spring 88 is secured to stud 91 fixed to bracket 74. Solenoid 86 is secured to the lower edge of bracket 74 which in turn is fixed to upper cross-frame 54 adjacent station S2. When the release mechanism is non-operative, armature 84 is extended and springs 82 and 88 are fully retracted.

When during the cyclic operation of the associated bowling pin spotting machine, pins are required by the pin spotting mechanism thereof, a control device (not shown) completes a circuit energizing solenoid 86. When solenoid 86 is energized, armature 84 thereof is retracted and spring 82 extended, pivoting arm 80 about stud 81. This rotation of arm 80 moves cam follower 78 in track 76 causing push bar 70 to be pivoted about stud 72 and into the space between rail 68 and rim 30. In this position, push bar 70 will engage pins 10 carried in pockets 66 and urge them over rail 68 and into pin aligning and transfer device T. This transfer device may be similar in construction and operation to that shown in Zuercher Patent 2,767,984. Since it forms a specific part of the invention, further disclosure thereof is omitted.

Each filler 64 is provided with a recess 65 between rail 68 and rim 30 which accommodates the passage of a filler 64 over push bar 70 when push bar 70 is in operative position as member 28 rotates fillers 64 past station S2. Also, if push bar 70 is actuated by solenoid 86 as a pin 10 is directly over it, the weight of the pin will be sufficient to overcome the force in spring 82 preventing arm 80 from rotating until the pin 10 passes over the push bar 70, which, when thus released, emerges into operative position to eject the next pin 10 engaged thereby.

When the pin spotting mechanism (not shown) no longer requires that pins be discharged at station S2, the control device (not shown) breaks the circuit energizing solenoid 86. Since solenoid 86 no longer holds armature 84, spring 88, extended when solenoid 86 was energized, operates to return armature 84 to its extended position. This in turn pivots arm 80 about stud 81, causing push

bar 70 to be withdrawn from operative position between rail 68 and rim 30. Pins 10 carried in pockets 66 on rail 68 will be carried past station S2 and returned to station S1, rotary member 28 acting as a pin storage member, until such time as solenoid 86 is again energized as described hereinabove.

To permit pin changing while member 28 is in operation, mechanism is provided to automatically remove unwanted pins from the machine. The pin changing mechanism comprises an arm 90, fixed to one end of a shaft 92 adjacent rail 68. Shaft 92 is rotatably mounted in sleeve 94 secured to bracket 96. Bracket 96 is in turn fixed to the underside of upper cross-frame 54 and inclined support 51. A handle 98 is provided at the other end of shaft 92 to actuate arm 90.

When it is desired to remove pins from play, handle 98 is rotated, which in turn rotates shaft 92 in sleeve 94 and pivot arm 90 into the space between rail 68 and rim 30. As pins 10 in pockets 66 are elevated toward station S2, they engage arm 90 and are cammed out of pockets 66, over rail 68 and into funnel 100 suitably secured by bracket 102 to inclined support 51 and by bracket 104 to upper cross-frame 54. Funnel 100 delivers all unwanted pins 10 thus discharged from rotary member 28 rearwardly into a suitable pin receptacle 101. Fillers 64 provided with recess 65 pass over arm 90, permitted arm 90 to remove pins from member 28 until all unwanted pins have thus been taken out of play. At that time handle 98 is again rotated pivoting arm 90 out of the space between rail 68 and rim 30 and allowing pins 10 in pockets 66 to again be delivered to station S2.

Thus a safe and efficient mechanism is provided for accomplishing pin changing while the bowling pin spotting machine employing a pin elevating mechanism embodying this invention maintains continuous operation.

What we claim is:

1. In a bowling pin spotting machine for use with a bowling alley having a pit at one end, mechanism for elevating bowling pins removed from the playing surface of said alley into said pit comprising an annular channel, means mounting said channel for rotation in a substantially vertical plane such that portions thereof pass successively through and out of said pit, means for rotating said channel, means for moving said pins in said pit into said channel as said successive portions thereof pass through said pit, pin supporting means spaced from said channel and forming therewith elongated areas of support extending generally in the direction of movement of said channel, means securing said pin supporting means on said channel for travel therewith, said pin supporting means being operative to support and hold pins in said channel against removal therefrom during the rotation of said channel, and mechanism located at a point remote from said pit for selectively releasing pins from said channel.

2. The invention defined in claim 1 wherein said mechanism includes a pin remover, and means for moving said remover into engagement with pins in said channel to effect the gravitational discharge of pins therefrom, whereby pins to be used in said pin spotting machine may be changed while said channel is in motion.

3. In a bowling pin spotting machine for use with a bowling alley having a pit at one end, a pin delivery station, mechanism for elevating bowling pins removed from the playing surface of said alley into said pit for delivery to said station comprising an annular pin seating and conveying device, means mounting said device for rotation in a substantially vertical plane such that portions thereof pass successively through and out of said pit, means for rotating said device, means for moving pins from said pit into said device as said successive portions thereof pass through said pit, said device including a pin supporting wall, an arcuate rail, means mounting said rail on said device and spaced forwardly of said wall and substantially parallel thereto for conveying pins freely held

thereby in said device against removal therefrom during the rotation of said device.

4. The invention as defined in claim 3 including pin release means mounted at a point remote from said pit, and mechanism for operating said release means to selectively release said pins held in said device.

5. Pin holding mechanism for use with a rotary pin elevating device of an automatic bowling pin spotting machine comprising an annular pin supporting wall, a circular pin supporting rail, means mounting said rail on said pin elevating device in substantially parallel relation with said wall and spaced therefrom a distance sufficient to provide means for conveying pins and holding pins supported by said wall and rail against removal therefrom during the rotation of said pin elevating device.

6. The invention as defined in claim 5 including release means selectively operable to effect the discharge of said pins from said units at a pre-determined location.

7. A pin elevating device for a bowling pin spotting machine associated with a bowling alley having a pit at one end thereof, comprising an annular channel of substantially U-shaped cross-section, means supporting said channel for rotation in a substantially vertical plane, a plurality of spaced pin holding pockets in said channel, means for rotating said channel to pass each of said pockets successively through said pit, means for moving pins in said pit removed from the playing surface of said alley into said pockets, pin supporting means spaced from said channel and forming therewith elongated areas of support extending generally in direction of movement of said channel, means securing said pin supporting means on said channel for travel therewith to hold pins in said pockets against removal therefrom during the rotation of said channel, a pin discharge station, and means operable at said station to release pins from said pockets.

8. The invention as defined in claim 7 wherein said last-named means includes a pin ejector, means mounting said ejector at said discharge station to engage pins conveyed thereto in said pockets and means for selectively operating said ejector to urge said pins from said pockets for gravitation out of said device.

9. A pin elevating mechanism for a bowling pin spotting machine associated with a bowling alley having a pit at one end thereof, comprising an annular channel of substantially U-shaped cross-section with radially inwardly directed side walls, said channel having a central aperture, a ring, means mounting said ring on the inner periphery of said channel, a plurality of rollers, means rotatably mounting said rollers at spaced points adjacent said ring to support said channel for rotation in a substantially vertical plane, a plurality of spaced pin holding pockets in said channel, means for rotating said channel to pass each of said pockets successively through said pit, a pin receiving station, means for moving pins in said pit removed from the playing surface of said alley into said pockets at said pin receiving station, a circular guide, means mounting said guide on said channel in axially spaced relation relative to said inner periphery thereof and adjacent said pockets to form with said pockets supporting means to retain said pins in said pockets against removal therefrom as said channel is rotated, a pin discharge station, and means selectively operable at said discharge station to release said pins from said pockets.

10. The invention as defined in claim 9 wherein said last-named means includes an arm, means pivotally mounting said arm for rotation into the space between said ring and said guide into said pockets as said pockets are moved past said discharge station, a solenoid, means connecting said solenoid to said arm and an operating circuit to selectively actuate said solenoid to rotate said arm into said pockets at said discharge station whereby said pins retained therein are urged over said guide and out of said pockets into a pin aligning and transfer device.

11. The invention as defined in claim 10 including a pin changing apparatus comprising an arm, means pivot-

ally mounting said arm at a pre-determined position between said pin receiving station and said pin discharge station for rotation between said ring and said guide and into said pockets as said pockets are rotated therewith, and a handle for rotating said arm such that when said arm is rotated between said ring and said guide, unwanted pins retained in said pockets are urged over said guide and out of said pockets whereby pins to be used in said pin spotting machine may be changed.

12. The invention as defined in claim 8 wherein said pin supporting means is operative to retain pins in said pockets against removal therefrom when said pins are not engaged by said pin ejector whereby said pins are carried in said pockets back to said pit.

13. The invention as defined in claim 10 wherein said means connecting said solenoid to said arm includes a cam track in said arm, a pivot, a cam follower mounted on one end of said pivot for travel in said cam track, and a spring connected at one end to the other end of said pivot and secured at the other end to the armature of said solenoid whereby, if a pin in said pocket is directly in the path of travel of said arm when said solenoid is energized, the movement of said arm will be suppressed until said pin has passed out of the path of travel of said arm, ensuring positive release of said pins from said pockets into the pin orienting and transfer device of said associated pin spotting machine.

14. Pin holding mechanism for use with a rotary pin elevating device with an automatic bowling pin spotting machine comprising an annular pin supporting wall, an arcuate rail, means mounting said rail on said pin elevating device in axially spaced relation with said wall to provide means for conveying pins and holding pins conveyed thereby against removal therefrom during the rotation of said pin elevating device, said pin elevating device having inwardly directed side walls, said device having a central aperture, spaced supports, means rotatably mounting said supports adjacent the inner periphery of said device and means for rotating said device on said supports in a substantially vertical plane.

15. A pin elevating device for a bowling pin spotting machine associated with a bowling alley having a pit at one end thereof, comprising an annular channel of substantially U-shaped cross section with radially inwardly extending side walls, said channel having a central aperture, an arcuate rim mounted adjacent the inner periphery of said channel, means supporting said rim and mounting said channel for rotation in a substantially vertical plane, a plurality of spaced pin holding pockets in said channel, means for rotating said channel to pass each of said pockets successively through said pin, means for moving pins in said pit removed from the playing surface of said alley into said pockets, an arcuate rail, means mounting said rail on said channel adjacent said pockets to hold said pins in said pockets against removal therefrom during the rotation of said channel, a pin discharge station, and means selectively operable at said discharge station to release said pins from said pockets.

16. The invention as defined in claim 15 wherein said channel mounting means includes rollers and means rotatably mounting said rollers at spaced points on the inner periphery of said channel to support said rim.

17. In a bowling pin spotting machine for use with a bowling alley having a pit at one end, mechanism for elevating bowling pins removed from the playing surface of said alley into said pit comprising an annular channel, a plurality of pin holding units in said channel, a pin receiving station, a pin discharge station, means for rotating said channel to travel said units in succession to and from said pin receiving station, and to and from said discharge station, means for directing pins into said units in said channel, a pin retaining device mounted in spaced relationship with said pin holding units on and coacting with said channel to hold said pins in said units as said units travel to and from said pin receiving station, and means at said discharge station to selectively release said pins from said units, said means holding said pins in said units including a circular rail, and means securing said rail to said channel adjacent said units whereby pins directed into said units at said pin receiving station upon rotation of said channel engage and rest in part on said rail and are held thereby against removal from said units as said pins are traveled toward said discharge station.

18. In a bowling pin spotting machine for use with a bowling alley having a pit at one end, mechanism for elevating bowling pins removed from the playing surface of said alley into said pit comprising an annular channel, a plurality of pin holding units in said channel, a pin receiving station, a pin discharge station, means for rotating said channel to travel said units in succession to and from said pin receiving station, and to and from said discharge station, means for directing pins into said units in said channel, pin retaining means spaced from said units and forming therewith elongated areas of support extending generally in the direction of movement of said channel, to hold said pins in said units during the movement of said channel, means securing said pin retaining means on said channel for travel therewith, ejecting means at said discharge station to selectively release said pins from said units, said ejecting means including an arm, means pivotally mounting said arm for rotation into said units at said discharge station, a solenoid, means connecting said solenoid to said arm, and an operating circuit to selectively actuate said solenoid such that when said solenoid is energized, said arm is rotated into said units as said units are traveled therewith and pins held therein are urged out of said units.
